DESIGN FOR A BELT FASTENER OR SIMILAR ARTICLE

Irving Geist, New York, N. Y.

Application May 5, 1943, Serial No. 110,132

Term of patent 7 years

To all whom it may concern:

Be it known that I, Irving Geist, a citizen of the United States, residing in New York city, in the county of New York and State of New York, have invented a new, original, and ornamental Design for a Belt Fastener or Similar Article, of which the following is a specification, reference being had to the accompanying drawing, forming part thereof.

Fig. 1 is a front elevational view of a belt fastener showing my new design, the opposite side presenting substantially the same appearance as the side shown.

Fig. 2 is an outer edge view thereof, the inner edge also being plain.

I claim:

The ornamental design for a belt fastener or similar article, substantially as shown and described.

IRVING GEIST.
